PATENTED JUL 26 1870

trusses:

Shepardson

Inventor
Henry C. Rogers

United States Patent Office.

HENRY C. ROGERS, OF VILLAGE OF SAUQUOIT, PARIS, NEW YORK.

Design No. 4,206, dated July 26, 1870.

DESIGN FOR A TRADE-MARK.

The Schedule referred to in these Letters Patent and making part of the same.

To all whom it may concern:

Be it known that I, HENRY C. ROGERS, of the village of Sauquoit, town of Paris, in the county of Oneida and State of New York, have originated and designed a new Trade-Mark for a Label for a Hoe, of which the following is a full, clear, and exact description, reference being had to the accompanying drawings making part of this specification.

My design consists of a card or label, having, at the left end, a picture of the blade of a hoe, on which are engraved or printed in letter-press the words "Self-sharpening Hoe;" on the top of the label, the words "Self-Sharpener;" on the right end, the words

"Self-Sharpener;" in the center, the words "H. C. Rogers, Patentee and Manufacturer, Utica, N. Y.;" and at the bottom, the words "Entered according to act of Congress in the year 1870, by H. C. ROGERS, in the Clerk's Office of the Northern District of the State of New York."

What I claim as my invention, and desire to secure by Letters Patent, is—

The design for a trade-mark, herein set forth.

HENRY C. ROGERS.
